US00D941344S

(12) **United States Design Patent** (10) **Patent No.:** **US D941,344 S**
Knowles et al. (45) **Date of Patent:** **** Jan. 18, 2022**

(54) **DISPLAY SCREEN OR PORTION THEREOF
WITH GRAPHICAL USER INTERFACE**

(71) Applicant: **General Electric Company**, Schenectady, NY (US)

(72) Inventors: **Adrian Jeremy Knowles**, Brookfield, WI (US); **Nicholas Heil**, Waukesha, WI (US); **Timothy E. Voiles**, Oconomowoc, WI (US)

(73) Assignee: **General Electric Company**, Schenectady, NY (US)

(**) Term: **15 Years**

(21) Appl. No.: **29/671,080**

(22) Filed: **Nov. 21, 2018**

(51) LOC (13) Cl. **14-04**

(52) U.S. Cl. **USPC D14/487; D14/495**

(58) **Field of Classification Search**

(57) **CLAIM**

The ornamental design for a display screen or portion thereof with graphical user interface, as shown and described.

DESCRIPTION

FIG. 1 is a front view of an electronic device with a display screen showing the claimed design;
FIG. 2 is a rear view thereof;
FIG. 3 is a left side view thereof;
FIG. 4 is a right side view thereof;
FIG. 5 is a top view thereof; and,
FIG. 6 is a bottom view thereof.

The inner dash-dot-dash broken-line rectangle in FIG. 1 shows the perimeter of a display screen and forms no part of the claimed design. The remaining dash-dot-dash broken lines in the figures show portions of an electronic device and form no part of the claimed design.

The dash-dash broken lines in FIG. 1 illustrate portions of a graphical user interface and form no part of the claimed design.

1 Claim, 6 Drawing Sheets
